UNITED STATES PATENT OFFICE.

and I, HENRY SYMES, do hereby declare the following to be my invention, which I desire to protect by Letters Patent, and for which I have made application to the Commissioner of Patents, at Washington, D. C., on the 9th day of November, 1916, Serial No. 130,422.

06 **1,327,500.** **Specification of Letters Patent.** **Patented Jan. 6, 1920.**

Application filed November 9, 1916, Serial No. 130,422.

To all whom it may concern:

Be it known that I, HENRY SYMES, a subject of His Majesty the King of Great Britain, residing at 91st Princes street, in the city 5 of Dunedin, in the British Dominion of New Zealand, have invented certain new and useful Improvements in Telephone Sets, and do hereby declare that the following is a full, clear, and exact description of the invention, 10 such as will enable others skilled in the art to which it appertains to make and use the same.

The instrument consists of a small box, containing the usual bell-set, an adjustable rheostat for obtaining the required voltage, 15 a condenser, and the usual induction coils, with a five way jack for connecting by a five way plug and the usual flexible cord with five wires to the telephone, which consists of 20 a micro-transmitter-receiver, and an automatic calling device, and controlled by the usual central switch, which however is furnished with additional contacts. The telephone may rest on fixed supports, either on 25 the bell-box or otherwise as preferred.

Referring to the accompanying drawing:— Figure 1 is a diagram of the units within the bell-box, and Fig. 2, is a diagram of the contacts and connections in the telephone, showing the central switch in its normal position. Fig. 3 is a plan view of the type of automatic calling device I prefer to use, and Fig. 4 is part side elevation and part section of the telephone, showing it in normal position 35 when in use, with the central switch kept partly (but not fully,) down by a device to be explained. A is the automatic calling device, shown on plan in Fig. 3, side elevation in Fig. 4, and back with the cover removed, in Fig. 2, showing the arm A² at the end of the usual spindle A³ that turns when the dial A⁴ is turned for calling, and automatically cuts out the receiver when calling, reconnecting same when the said 45 call is finished, by closing the spring contacts A¹. When the dial is operated, as in the act of calling a subscriber, as shown by Fig. 2, the said arm is moved away from the contact A¹, and the latter being yielding or 50 of spring character will break the circuit because the spring contacts A¹ are, under these conditions, permitted to separate, and when the dial is restored to normal position, the contacts A¹ are caused to become engaged, 55 thereby restoring the circuit for calling purposes. This feature of improvement is par-

ticularly advantageous in eliminating noises during the operation of calling. B is the usual bell-set, B¹ the bell connection for cutting out the bell when needed, and automatically connecting up when the switch is in its normal position, see Fig. 2. When the switch is pressed, the bell is cut off, see Fig. 4. C is the condenser, I the usual induction coils, L¹ L² the usual lines to the exchange, L³ is the line connection within the telephone, P the primary connection within the telephone, R the rheostat, R¹ is the usual receiver, R² is a variable resistance device, governed by a lever, (not shown,) for obtaining the desired voltage, which may thus be increased to combat indistinctness arising from distance or unfavorable weather conditions. R³ is a connection from the receiver within the telephone. S is the central switch 75 insulated as usual along its upper edge. T is the micro-transmitter, of preferred sanitary type as shown.

The several circuits are defined as follows:

Bell circuit.—Normally the cam in the 80 automatic caller A presses on the contact A' closing the same, but the circuit is not complete in view of the fact that the variable resistance controlling device R² is open or the circuit is incomplete therethrough. When 85 receiving, the contact A' is closed and the current passes through the secondary coil in the usual manner and also through the condenser, the bell wire in this circuit being utilized through the jack 5. When speaking, 90 the circuit is through the primary coil, the proper reduced voltage being extracted from the rheostat and in this instance also the bell wire is utilized through the jack 5. It will 95 be understood that the jacks 4 and 5 provide for the making of circuit ways and by utilizing the bell wire for a portion of its length, it is possible to get all of the connections or circuits for the various working characteristics of the instrument. It must 100 be borne in mind that the contact A' is always closed except when a call is made when it is in position as shown, the said contact being fixed to the spindle of the moving ring shown in Fig. 3, which in practice is numbered. Should the user wish to speak to others in his room, and not be heard at the other end of the wire and still hold the exchange, the transmitter has only to be tilted slightly forward so that the sliding weight 110 W falls over the point of the switch, see Fig. 4. This breaks the primary circuit as

shown, while by taking up the telephone the weight W drops away automatically when the switch is again pressed. The releasing of the switch, S disconnects the telephone 5 from the exchange when it is then ready for another connection. The line circuit is not broken when the sliding weight W allows the speaking contact to break at P and it takes in the whole rheostat. The release of the 10 weight W when taking up the hand set for use is accomplished by pressing on the switch S, this latter action allowing the weight W to fall away.

It will be seen that the weight W does not 15 hold the switch S sufficiently down to connect at P while it is sufficiently down to disconnect at B¹.

It will also be seen that only one hand is 20 necessary to use this telephone. In this invention any suitable materials or sizes may be adopted.

The particular novel features in this improvement are that the parts now ordinarily scrapped because they cannot take the higher 25 currents of the automatic system are used by merely abstracting the necessary voltage needed for these ordinary scrapped parts which are of low voltage from the coil R at R². Moreover, in the present instance the 30 automatic calling device or caller on the receiver which is of well-known form has a compact arrangement relatively to the remaining parts of the telephone set and also permits the use in connection therewith of 35 wires of the receiver on which the said caller is disposed that are usually dead, thereby saving many connections that would otherwise be necessary. When speaking, the bell wires are dead, and after use of the telephone 40 it will be understood that the said wires become active or are charged and alive ready for service. The transmitting and receiving elements disclosed are of the class not now admissible in automatic work, but, 45 when connected to the coil R at R², the said transmitting and receiving parts are rendered practically operative and great saving in the use of telephone elements results.

Having now described the invention I desire 50 a patent of the United States of America for:—

1. In a telephone of the class specified adapted for automatic telephone work, the combination with an automatic calling de-

vice and a transmitter and receiver mounted 55 on and embodied in the organization of the same, of a bell set, a condenser, an adjustable rheostat, and induction coils all electrically connected to said calling device and the transmitter and receiver, and a switch associated with a weight device automatically movable to press one end of the switch and released for gravitating action by the switch to control the operation of said telephone parts and also to cut off the bell set when 60 receiving messages, the weight device also being automatically operative to cause sounds to pass the user of the telephone when the latter drops away upon resumption of the latter for use in talking purposes. 70

2. In a telephone of the class specified adapted for automatic service, the combination with a transmitter and receiver, of an automatic calling device mounted on the receiver and operative to cut off the latter 75 while calling and also to automatically reconnect the said receiver when the calling is finished, a bell set, a condenser, a rheostat, and induction coils all electrically connected to the transmitter and receiver and calling 80 device, and a switch having an automatic device co-operating therewith for controlling the operation of the several elements.

3. In a telephone of the class specified, the combination with a transmitter and receiver 85 and an automatic calling device mounted on the receiver and operative to cut off the receiver when a call is being made, of a bell set, a condenser, an adjustable rheostat, and induction coils electrically connected up to 90 the receiver, transmitter and calling device for actuation during the several telephone operations, and a central switch having a sliding weight operative in relation to one end thereof to maintain connection with an 95 exchange and released by the actuation of the switch, the said sliding weight slipping away from the end of the switch when the telephone instrument is used for talking purposes. 100

In testimony whereof, I have hereunto set my hand in presence of two subscribing witnesses.

HENRY SYMES.
